GARAGE DOOR OPERATOR

Adolf G. Krocker, Waco, Tex.

Application September 1, 1938, Serial No. 227,998

3 Claims. (Cl. 268—30)

This invention relates to garage door construction.

An object of this invention is to provide a strong and durable garage door construction, and an operating mechanism therefor, having means which may be operated from a driver's seat of a car either approaching or leaving the garage, to open or close the garage door.

Another object of this invention is to provide a garage door pivoted within the garage on a horizontal pivot and normally in vertical position to close the garage, and adapted to be swung upwardly about said pivot to horizontal position for opening the garage, said garage door being provided with counter-balancing weights hidden in the hollow walls of the garage, the top portion of the door jamb being provided with shock absorbing bumpers adapted to be engaged by the door when the latter is either in closed vertical position or open horizontal position, the side portions of the door jamb being further provided with vertical members adjustable inwardly toward each other to vary the width of the door opening for accommodating doors of somewhat varying widths.

Yet another object of this invention is to provide a garage door of the character described, and means for opening or closing the garage door from the outside of the garage by drivers of cars either approaching or leaving the garage, said means including a handle which may be pulled to either open or close the door, the handle being mounted on a swivel so that it may be turned in various directions, whereby the same may be conveniently grasped by the driver when the car is either a little forward or a little back.

A further object of this invention is to provide garage door construction of the character described, which shall be relatively inexpensive to manufacture, and which shall be smooth and positive in operation, easy to operate and yet practical and efficient to a high degree in use.

Other objects of this invention will in part be obvious and in part hereinafter pointed out.

The invention accordingly consists in the features of construction, combinations of elements, and arrangement of parts which will be exemplified in the construction hereinafter described, and of which the scope of application will be indicated in the following claims.

In the accompanying drawings, in which is shown one of the various possible illustrative embodiments of this invention,

Fig. 1 is a front elevational cross-sectional view of garage door construction with opening and

closing mechanism therefor, embodying the invention;

Fig. 2 is a cross-sectional view taken on line 2—2 of Fig. 1; and

Fig. 3 is a cross-sectional view taken on line 3—3 of Fig. 1.

Referring now in detail to the drawings, 10 designates a garage provided with a door 11 and mechanism 12, embodying the invention for opening and closing the door from the driver's seat 10 of an automobile either approaching or leaving the garage. The garage 10 has side walls 13; and a front wall 14 having a door opening 15. At the door opening 15 is a door jamb 16.

The side walls 13 of the garage have outer wall 15 portions 13a and inner wall portions 18, spaced from the outer wall portions by spaced upright beams 19. Between a pair of adjacent upright beams 19 at each side wall 13, is a vertical compartment 20, comprising parallel walls 21 fixed 20 to a pair of adjacent beams 19, and a wall 22 parallel to the outer wall portion 15. The walls 21 closer to the door opening 15 are formed with vertical slots 23, for the purpose hereinafter appearing.

Fixed to the underside and rear edge of the top portion of the door jamb 16, are elongated rubber strips or bumpers 24 and 25 serving as shock absorbers for the garage door 26 when the latter is moved to open or closed position, as will appear hereinafter.

Fixed to the rear edges of the vertical portions of the door jamb 16 are a plurality of screws 28, serving to adjustably attach to the door jamb, a pair of vertical strips 29, having horizontal slots 30 through which the screws 28 pass. It will now be understood that by loosening the screws 28, the strips 29 may be moved inwardly or outwardly to accommodate the width of the door 26.

The door 26 is rectangular and may be of laminated or multi-ply wood made in a single slab, or more than one piece held together by a pair of end cross-pieces 33, at the lower and upper ends of the door, and a pair of intermediate cross-pieces 34 and 35 parallel to said end pieces 33.

Fixed to the intermediate cross-pieces 34 and 35 are a pair of similar, symmetrically disposed supporting brackets 36. Each bracket 36 comprises a portion 38 extending downwardly from the cross-piece 36 and disposed perpendicularly 50 to the door 26. Interconnecting the lower end of portion 38 with an end of the cross-piece 34, is an inclined portion 39, having an extension 40 passing through the slot 23 in the wall 21, into the compartment 20. A brace 42 fixed to mem-

bers 39 and 40 serves to strengthen the same. Portions 38 and 39 of the bracket are interconnected by a reinforcing brace 43.

Extending from the lower end of portion 38 of 5 one of the brackets, is an arm 45, disposed parallel to the door 26 and terminating somewhat short of the door opening 15. At the junction of the portions 38 and 39 of each bracket 36 are horizontal pivot openings to receive aligned horizontal 10 pivot pins 47 on plates 48 fixed to the beams 19. The door 26 is thus mounted for pivotal rotation about the axis of pivot pins 47, said axis being located in back of the door opening and below the top of the door opening.

15 When the door is in horizontal open position in contact with the bumper 24, the arm 45 is in horizontal position. When the door is swung downwardly to vertical closed position, the arm 45 is in downwardly extending vertical position.

20 The extensions 40 of the brackets 36 are formed with a plurality of openings 50, whereby to adjustably fix a counter-balancing weight 51 on each of said arms. Each counter-balancing weight 51 has a diametric groove 52 to receive the 25 extension, and a central bolt 53 passes through the weight and through one of the openings 50. Attached to the lower end piece 33 is a cord 55 which may be grasped for pulling the door down to closed position.

30 Means is provided however for opening or closing the door 26 from the outside of the garage by a driver of a car either approaching or leaving the garage. To this end, there is fixed to the driveway 60 in front of the garage, an upstanding 35 post 61 having a vertical through opening 62, and an enlarged socket 63 at its upper end. The post 61 is preferably aligned with one side of the garage, so as not to interfere with cars passing into and out of the garage.

40 Extending through the opening 62 is a pipe 65 passing downwardly through the post and through the ground beneath the driveway 60, as at 67, and upwardly into the garage, as at 68, adjacent one side of the door jamb. The portion 45 68 of the pipe is fixed to one of the inner wall portions 18 by a bracket 69. Fixed to the upper end of the pipe portion 68 is a support for a pulley 70.

45 Fixed within the socket 63 at the upper end of 50 the post 61 is a cylindrical socket member 71, open at the top and having a central opening communicating with pipe portion 65. Swivelled within the socket member 71, is a swivel member 55 72 having a bottom wall 73 contacting the bottom wall of the socket member 71, a cylindrical wall 74 contacting the inner surface of the cylindrical wall of the socket 71, and an outwardly 60 extending flange 75 at the upper end of the cylindrical wall 74. Extending upwardly from the bottom wall 73 of the swivel member 72 is a pipe portion 76, aligned with the pipe portion 65.

65 Pivoted to the flange 75 is a link 78, to the upper end of which there is pivotally connected a handle member 79. Extending through the pipes 67, 68 and 69 is a flexible cord, cable, chain or other flexible member 80, contacting the pulley 70 and connected at one end to the arm 45. The flexible member 80 also passes through the pipe portion 76 and is connected at the other end to 70 the link 78.

75 It will now be understood that when the door 26 is in the open position illustrated in Fig. 1 of the drawings, a pull on the handle 79 will cause the flexible member 80 to pull downwardly on the arm 45 to swing the door 26 downwardly to closed

position. As the arm 45 swings downwardly from horizontal to vertical position, it will again pull the flexible member outwardly, so that one end thereof extends in a horizontal position, as shown in dotted lines in Fig. 1 of the drawings. 5

When the door is in closed position, a pull on the handle 79 will swing the door upwardly to horizontal open position. As the door 26 moves up or down, it will strike the bumpers 24 or 25, which absorb the shock. 10

It will now be understood that the swivel member 72 may be swivelled about a vertical axis, so that the handle 79 may extend in a plurality of radial positions, whereby it may be more easily grasped if the car is a little back or a little forward. 15

It will thus be seen that there is provided a device in which the several objects of this invention are achieved, and which is well adapted to meet the conditions of practical use. 20

As various possible embodiments might be made of the above invention, and as various changes might be made in the embodiment above set forth, it is to be understood that all matter herein set forth or shown in the accompanying drawings is to be interpreted as illustrative and not in a limiting sense. 25

Having thus described my invention, I claim as new and desire to secure by Letters Patent:

1. In combination, a garage having a door opening, a door to cover said opening, a pair of horizontal, aligned pivots on opposite sides of the door opening, located rearwardly of the door opening and below the upper end of the door opening, a pair of brackets fixed to opposite sides of the door and engaging said pivots, one of said brackets having an arm disposed parallel to the door and extending from one of said pivots toward the bottom end of the door, and means for moving said door from vertical position, closing said door opening, to horizontal open position, at the upper end of said door opening, said means comprising a vertical tubular member within said garage, located in the plane of said arm, the upper end of said tubular member being located below said pivots and between said pivots and door opening, and a flexible member extending through said tubular member, and connected to the outer end of said arm. 35

2. In combination, a garage having a door opening, a door to cover said opening, a pair of horizontal, aligned pivots on opposite sides of the door opening, located rearwardly of the door opening and below the upper end of the door opening, a pair of brackets fixed to opposite sides of the door and engaging said pivots, one of said brackets having an arm disposed parallel to the door and extending from one of said pivots toward the bottom end of the door, means for moving said door from vertical position, closing said door opening, to horizontal open position, at the upper end of said door opening, said means comprising a vertical tubular member within said garage, located in the plane of said arm, the upper end of said tubular member being located below said pivots and between said pivots and door opening, a flexible member extending through said tubular member, and connected to the outer end of said arm, and a pulley rotatably supported at the upper end of said tubular member, said flexible member being adapted to engage said pulley. 55

3. In combination with a garage having a front wall formed with a door opening, a door for said door opening, a pair of aligned, horizon- 70 75

tal pivots located rearwardly of the door opening and below the upper end of said door opening, a door for said garage, a pair of brackets on said door, pivoted to said horizontal pivots, an upstanding post located in front of the garage, a pipe passing downwardly through said post, beneath the driveway, and upwardly into the garage adjacent one side of the door opening, the upper end of the post being formed with a socket, a member swivelled within said socket and having an upstanding pipe aligned with the portion of the pipe which passes through the

post, a flexible member passing through the pipe in the post and beneath the driveway and in the garage, and through the pipe portion of the swivelled member, an arm on one of said brackets, disposed parallel to the door and extending from one of said pivots toward the bottom end of the door, one end of the flexible member being connected to the outer end of said arm, and a member pivoted to said swivelled member, and connected to the other end of said flexible member.

ADOLF G. KROCKER.
